UNITED STATES PATENT OFFICE.

FREDERICK M. VENZIE, OF PHILADELPHIA, PENNSYLVANIA.

BUILDING STRUCTURE.

Application filed December 16, 1925. Serial No. 75,686.

This invention, generally stated, relates to a building structure and has more especial relation to a floor or like construction of concrete.

5 According to accepted methods of building concrete floor and like structures it is quite difficult and expensive to attach metal lath in place to receive ceiling plaster, usually requiring the services of skilled mechanics.

10 The leading object of the present invention is to overcome the above described disadvantageous features and provide a structure of the character stated in which a floor or the like is provided combining efficiency, 15 simplicity, and cheapness, and in which unskilled labor may be successfully employed in the erection of metal lath to receive the ceiling plaster.

Other and further objects not at this time 20 appearing will be hereinafter referred to.

The invention consists of the novel construction hereinafter described and finally claimed.

The nature, characteristic features and 25 scope of the invention will be more fully understood from the following description taken in connection with the accompanying drawings forming part hereof, and in which:

Fig. 1, is a fragmentary view in section 30 illustrating a floor structure in accordance with the invention in which the concrete is poured upon the forms.

Fig. 2, is a similar view with the forms removed and the metal lath secured in position for ceiling plaster reception.

Fig. 3, is an enlarged view in cross section of a piece of form having nailed thereupon a metal lath attachment device, prior to pouring of concrete.

40 Fig. 4, is a similar view illustrating the concrete poured, the form removed and the metal lath in place.

Fig. 5, is a view in cross-section of one of the metal lath attachment devices detached; and

Fig. 6, is a view thereof in plan.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my in-

vention is not limited to the precise arrangement and organization of the instrumentalities as herein shown and described.

In the practice of the present invention the usual forms 1 are erected and supported or shored up by beams 2, as seen in Fig. 1. The next step, as best seen at the right hand side of Fig. 1 is to secure upon the upper faces of the forms 1, a plurality of spaced, metal lath, attachment devices, best seen in Figs. 3 to 6. Each attachment, which is designated 3, is composed of thin metal stamped from a single piece of material to a shape which may be likened to that of a boat, see Fig. 6, and each are secured in inverted position as by a nail 4, to the upper face of a form 1, best seen in Fig. 3. The tapered ends of each attachment 3 are longitudinally split as at 5, so that in nailing an attachment to place the same will yield sufficiently to effect a good tight connection so that when the concrete 6 is poured the said attachments will not shift. The opposed side walls of an attachment are notched as at 7 adjacent each end of an attachment. Extended laterally across the attachment at 8, see Fig. 5, and engaging opposed notches are a pair of wire members, the free ends being first extended upwardly at 9 over the curved wall of the attachment, the said ends then being twisted together at 10 and the free ends of the wire members being extended laterally in opposed relation as at 11. The concrete 6 having been poured to form the floor, obviously the metal lath attachments 3 are firmly embedded therein. This position of parts is seen in Fig. 1. With set of concrete 6 obtained the forms 1 are removed thus exposing upon the underside of the floor a plurality of spaced attachments 3 with the wire parts 8 extended across each attachment.

It is to be understood that with the removal of forms 1 the nails 4 are left hanging within the cavities of the attachments 3. Metal lath of any desired type, as for example wire mesh 12, is now positioned to receive ceiling plaster 13, see Fig. 2. In securing the wire mesh 12 in place the same is wired as at 14 to the exposed wire members 8 as best seen in Fig. 4. While the above described structure is adapted for any desired form of floor, ceiling or like structure it is especially efficient where ceiling beams are formed, as shown in the drawings, because

the metal lath can be stretched taut and very easily wired to the attachments which latter may be positioned upon both side and bottom walls of a beam.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim as new is:

A metal lath support for concrete construction comprising an inverted substantially boat-shaped device having a continuous upper convexed surface throughout its length, the free pointed ends thereof being longitudinally slotted, the open bottom of which has extended thereacross a wire member the ends of which are extended upwardly around the upper surface of said device and twisted together with the free ends thereof extended in opposed relation, 25 transversely to the longitudinal axis of said device.

In testimony whereof, I have hereunto signed my name.

FREDERICK M. VENZIE
